UNITED STATES PATENT OFFICE.

EDWIN J. QUINBY, OF PORTLAND, MAINE.

TELEPHONE RECEIVER.

No. 865,937.

Specification of Letters Patent.

Patented Sept. 10, 1907.

Application filed November 22, 1905. Serial No. 288,616.

To all whom it may concern:

Be it known that I, EDWIN J. QUINBY, a citizen of the United States of America, and a resident of Portland, Cumberland county, State of Maine, have invented 5 certain new and useful Improvements in Telephone Receivers, of which the following is a specification.

My invention relates to a telephone receiver of that class which are commonly used and which hang on a bifurcated hook. These telephone receivers are composed of hollow elongated casings of hard rubber generally cylindrical in form. One end is enlarged to engage the hook of the telephone and the other end is also enlarged to receive the ear piece which is generally screwed to it.

10 The diaphragm and the magnet are secured to the body of the casing inside. These receivers are frequently dropped while being used and when they strike against the wall or other hard object they are frequently broken and it is to remedy this frequent breakage and to provide a receiver which is sufficiently tough

20 to stand hard knocks that is the object of my invention. The invention consists essentially of forming the casing of the receiver of metal, preferably of sheet brass or steel, fitting inside of the casing at the flaring end and 25 secured thereto a bushing composed of insulating material into which the magnet fits and by which it is held out of contact with the casing.

I illustrate my invention by means of the accompanying drawing in which:

30 Figure 1 is a part longitudinal section and part side elevation of a receiver constructed according to my invention and Fig. 2 is an end elevation with portions cut away.

In the drawing A represents the magnet provided 35 with an upper head A', B the diaphragm and C the ear piece of the receiver these parts being common and well known. The casing D has the common shape being generally cylindrical and larger at each end than in the middle, one end being slightly enlarged to engage 40 the hook and the other end flaring to the size of the ear piece.

The casing is made of hollow metal preferably of spun brass and it consists as here shown, of the casing proper and a cap d at the hook end fitting into the end of the 45 casing and which is preferably secured to the casing proper by brazing or soldering. The cap d has a cen-

tral opening into which is screwed the insulating bushing e through which passes the cord not here shown. The ear piece C fits in the enlarged end of the casing and is preferably composed of insulating material. It 50 is secured to the casing as here shown by one or more screws c passing through right angle openings e' in the edge of the casing and entering the edge of the ear piece. The magnet is held in the metal casing and out of contact therewith by means of a bushing F of insulating material and formed to fit the flaring portion of the casing. It is secured in place by screws f or other suitable means and a rim f' is formed on it to insulate the edge of the magnet from the metal of the casing. The bushing is so formed that the magnet A will fit into it and 60 the magnet head, which fits within the rim f', is shown as being fastened to the upper edge of the bushing by screws a. A tight fit of the head within the rabbet formed at the outer end of the bushing F is insured by flaring the inner surface of the rim f' to correspond with 65 the external flare of the periphery of the head. The screws a thus serve to force the head into its seat with a wedging action. The bushing thus completely insulates the magnet from contact with any metal and it is as effective as if the entire receiver was constructed of 70 insulated material.

The receiver thus described will stand a good deal of hard usage without breaking and it can be much more cheaply made than the ordinary kind.

It will be understood that the bushing F is formed 75 according to the form of the magnet to be used, the outside fitting the casing and the opening and upper end being formed to fit closely to the magnet.

I claim:

A telephone receiver consisting of a hollow metal casing flared at its outer end, an insulating bushing secured 80 within such flaring portion and formed with an internal rabbet in its outer end, the rim of said rabbet being flared internally, the magnet, a magnet head supporting the same and seated within said rabbet, the periphery of said head 85 being flared to correspond with the flare of said rim, and means connecting the head and bushing for forcing said head into seated position.

Signed at Portland, Maine this 9th day of November 1905.

EDWIN J. QUINBY.
